DRAFTSMAN:

D5,819

UNITED STATES PATENT OFFICE.

JACOB BEESLEY, OF PHILADELPHIA, PENNSYLVANIA, ASSIGNOR TO
CHARLES NOBLE & CO., OF SAME PLACE.

DESIGN FOR A COOKING-RANGE.

Specification forming part of Design No. 5,819, dated April 30, 1872.

Specification describing a Design for the Plates of a Cooking-Range, invented by JACOB BEESLEY, of the city of Philadelphia, in the State of Pennsylvania.

The nature of my design is fully represented in the accompanying photographic illustration, to which reference is made.

A represents the front plate of the oven, with its door and clean-out plate applied thereto; B, the front plate of the ash-pit; C, the jamb-plate; and D, the damper-plate.

The plate A has the oven-door a' , cast with an edge-molding supporting a flat face, a'' , which has a bas-relief ornamental figure, a''' , in its center; and just below the closed door a' is the clean-out plate a^4 ; and below the said clean-out plate a^4 there is an ornamental bas-relief figure, a^5 ; and below this figure a^5 is the ornamental base a^6 . The plate of the ash-pit B has in its center an oscillatory draught-plate, b' , over a corresponding circular arrangement of openings, partly surround-

ed by an ornamental border, in bas-relief, b'' , and an ornamental base corresponding in ornamentation with the base of plate A. The jamb-plate C has a raised face, c' , upon which are the bas-relief ornamentalations $c'' c'''$, and an ornamental base, c^4 , corresponding with the bases, respectively, of plates A and B. The damper-plate D has the word "Liberty" in bas-relief letters upon its surface d' .

I am aware that the general form of the plates described is not new, and I do not claim them. The distinctive character of my design is found in the ornamentalations referred to in the foregoing description.

I claim as my invention—

The design for the ornamentation of the plates of a cooking-range, as shown and described.

JACOB BEESLEY.
